ATTORNEY.

UNITED STATES PATENT OFFICE

112,976

DESIGN FOR A GOGGLE

Joseph Brunetti, Carlstadt, N. J.

Application October 7, 1938, Serial No. 80,298

Term of patent 7 years

To all whom it may concern:

Be it known that I, Joseph Brunetti, a citizen of the United States and resident of Carlstadt, in the county of Bergen and State of New Jersey, have invented a new, original, and ornamental Design for a Goggle, of which the following is a specification, reference being had to the accompanying drawing, forming a part thereof, and of which Figure 1 is a perspective view of a goggle showing my new design, Fig. 2 is a top plan view thereof, one of the temples being shown in fragmentary condition for convenience of illustration, Fig. 3 is a view thereof in side elevation, Fig. 4

is a sectional view thereof on the line 4—4 of Fig. 3, and Fig. 5 is a sectional view taken on the line 5—5 of Fig. 1.

The characteristic feature of the design consists in the enlarged temples in combination with the angular walls which extend at right angles to the eye piece frame at each end thereof and form corner pieces to which the temples are connected.

I claim:

The ornamental design for a goggle, substantially as shown and described.

JOSEPH BRUNETTI.
